UNITED STATES PATENT OFFICE.

JAMES R. HYDE, OF TROY, NEW YORK.

IMPROVEMENT IN COOKING-STOVES.

Specification forming part of Letters Patent No. **150,047**, dated April 21, 1874; application filed February 9, 1874.

To all whom it may concern:

Be it known that I, JAMES R. HYDE, of the city of Troy, in the county of Rensselaer and State of New York, have invented certain Improvements in Cooking-Stoves for burning bituminous and other coal, and in warming closets and water-reservoirs, of which the following is a specification:

The nature of my invention relates to improvements in cooking-stoves for burning bituminous and other coal, and in warming closets and water-reservoirs, water-tanks for generating steam, their combinations with, and their attachments to, such stoves, reference being had to Letters Patent granted to me for and upon improvements in cooking-stoves and reservoirs, dated March 11, 1873, and June 17, 1873; also, application for further improvements in such stoves, warming-closets, and reservoirs, filed in the Patent Office January 21, 1874; and it consists in constructing an air-chamber on the sides and ends of the fire-box, divided by a vertical partition-plate near the center, in front. Into this chamber air from the room is admitted, either in front and on each side of said partition-plate, or from the bottom of the stove, through ducts placed near the front corners of such stove, to and into such chamber. The air thus admitted into such chamber becomes highly heated, and is used for heating the oven, reservoir, and warming-closet. It passes from such chamber through a flue at the back of the fire-box and in front of the oven, down to and along the bottom and up the back of the oven, to and past a valve to the smoke-pipe, or through a valve in the back-end plate of the stove into a flue at the bottom of the reservoir, along the bottom, up the back, and across the top of said reservoir into the smoke-pipe; or it may be let into the room through a valve at the top of the reservoir. When the reservoir and warming-closet are detached from such stove, the heated air may be let into the room through the valve in the rear end plate of the stove. It also consists in the employment of a valve in the front part of the bottom oven-plate; also, a valve in the rear-end plate of said oven; so as to pass a current of heated air into, or into and through, the oven. It also consists in attaching water-tanks (in which to generate steam)

to each side of the stove, at the end of the fire-box, connected by tubes with a hollow ring or chamber, located at the top of the heating-chamber, and forming the top part of the fire-box. Into this ring or chamber air is let in from the room, and steam from the water-tanks, and such air and steam pass into the fire-chamber in small jets through apertures in said ring, at or near the top thereof. Such heated air and steam will mingle with the gases arising from the burning fuel, thereby aiding combustion, and burning the smoke. In connection with the heating-chambers and hot-air flues, a single smoke or draft flue is employed, extending from the fire-chamber directly to the smoke-pipe, thus dispensing with diving or return smoke-flues around the oven, all of which is hereinafter more fully described.

Figure 1 is a longitudinal vertical sectional view of my stove, reservoir, and warming-closet. Fig. 2 is a plan view of such stove taken at *x x*, Fig. 1, as shown by the dotted lines, having part of the fire-box and most of the oven removed. Fig. 3 is a plan view of the rear part of the stove-top *A*, showing the piece *P* in position when the reservoir is removed. Fig. 4 is a vertical cross-section of such stove taken at *y y*, Fig. 1, showing the water-tanks, heating-chambers, &c. Fig. 5 is sectional views of parts of the stove-top *A*, having recesses therein; also, the bearing-pieces of the reservoir, which fit into such recesses.

Like letters refer to like or corresponding parts in all the drawings or figures.

A represents the boiler-hole top of a cooking-stove made in any of the known ways, except as hereinafter stated; *B*, the flue-space over the oven, from the fire-chamber to the exit-pipe. *T* is a plate attached to the stove-top, to depress and spread out the current of gases or smoke at the rear part of the oven, before its entrance into the exit or smoke pipe. *C* is the fire box; *D*, the ash-pit; *E*, the oven; *F* and *G*, hot-air spaces or flues under the oven and at the back thereof; *H*, the warming-closet; *I*, the water-reservoir, mounted together, and attached to, the rear end of the stove. Around the fire-box *C* is formed an air-chamber, *L*, extending entirely around the

sides and ends thereof, and may be provided with a vertical partition in front, as at M, Fig. 2. Cold air is admitted into this chamber L through flues V, extending from the bottom of the stove to and into said chamber L at or near the front corners of such stove, or through the front plate and on each side of the partition M, as shown at K, Fig. 2. These inlets for cold air should be provided with valves, so as to regulate the quantity of air to be admitted. The air thus admitted into this chamber or space L becomes highly heated, and passes therefrom, as indicated by the arrows in Figs 1, 2, and 3, around the fire-box and down the flue N in rear of said fire-box, and in front of the oven to and along the bottom flue G, and up the back flue F to the slide d, and through the opening O into the flue n on the bottom of the reservoir I, and at the top part of the warming-closet up the flue n' to and along the flue n'' to the smoke-pipe J; or, by the use of the slide-valve k, by moving it toward the stove, the air will pass into the pipe J. When moved from the stove it will pass into the opening or pipe w. Said heated air will pass through said pipe w to an upper room. If such pipe is not attached to said flue the heated air will be let directly into the room where the stove is. The heated air, as it passes along the flue n, expands into the spaces f between the outside wall and the lining t of the reservoir. Said lining t is a little the smallest at the bottom, so that a small space is left all around. The heated air may be let directly into the pipe J from the flue F through opening O' in the slide d, which is so constructed that, by moving the knob e, it will open O' and close O, or vice versa; or there may be two separate valves, one for O, the other for O'. Instead of valve k there may be two valves operated separately. In the hot-air flue or space under the oven are vertical plates R, extending from the stove-bottom to the oven-bottom, placed in an angular form, as at R R, Fig. 2, and they are for the purpose of spreading the heated air toward the outer parts of the oven. There are small openings S in these vertical plates to admit a portion of the current of heated air to the central parts of the oven-bottom. There are no diving or return smoke-flues at the back or under the bottom of the oven. There is a valve, s, in the front part of the bottom oven-plate; also a valve, r, in the rear vertical plate of said oven. These valves are for the purpose of admitting a current of heated air into or through the oven, and for ventilating it one or both may be opened at the same time. When the reservoir and warming-closet are removed from the stove, the heated air may be let into the room or into the smoke-pipe by the use of the slide d through valve O or O', or two separate valves can be used. There is a chamber, c, all around and forming the top part of the fire-box above the chamber L. There are water-tanks U attached to each side of the stove or at each end of the fire-box.

These tanks are provided with tight-fitting covers b, also connecting-tubes a leading from said tanks to and into said chamber c. Steam is generated in these tanks U, and passes through the connecting-tubes a into the chamber c. Air is admitted from the room through the front plate of the stove, or through the sides of such stove, or through pipes or ducts from below the stove, into the chamber c. The steam and air thus admitted mingle together, and pass through small apertures in the upper part of said chamber c, in small jets of hot air and steam, into the fire-chamber, and there mingle with the gases arising from the burning fuel, and materially aid combustion, and burn the smoke or soot.

In burning bituminous coal much difficulty is found in clogging or filling up the flues with soot, which is obviated in this stove, there being a direct draft only from the fire-chamber to the exit-pipe.

Fig. 3 is a view of the rear part of the stove-top A, having the piece P fitted therein to make a finish of the stove-top when the reservoir is not in use. Dotted lines show the space between the projecting parts i of the stove-top A; also the length of the reservoir at that point. The ends of the piece P are fitted into the recesses j of the stove-top. The reservoir and warming-closet are mounted together, so as to form but one piece, and can be readily attached to or detached from such stove.

By this construction a large saving is obtained both in the shipment and in the setting up of such stoves, reservoirs, and warming-closets for use.

The manner of attaching the reservoir and warming-closet to the stove is by extending or projecting a portion of the stove-top A at the rear corners, as shown at i, Figs. 1, 3, and 5, having recesses therein, (either circular or beveled in form,) as shown at j or h, Figs. 1 and 5. On each end, near the front corners of the reservoir, are projecting bearing-pieces m formed to fit into the sinks or recesses j or h in the extended or projecting parts i of the stove-top. The reservoir and warming-closet at the top part thereof are fitted in between the projecting parts i of the stove-top, and rests upon the pieces m, which fit into the recesses j in the top A, and against the back part of the stove, and will be thereby held firmly in position without the use of bolts, screws, ears, eyes, hooks, or slots through the top plate of the stove.

I do not claim the heating-chamber L around the fire-box, or the inlets or ducts for the admission of air therein, or the perforated ring or chamber c, separately, or as claimed in the Letters Patent granted to me upon improvements in cooking-stoves, water-reservoirs, and warming-closets, dated March 11, 1873, and June 17, 1873; nor do I claim what is covered by claims in a pending application for a patent upon improvements in cooking-stoves, reservoirs, and warming-closets, filed January 21, 1874. I do not claim the particular flues or

valves about the reservoir, as claimed in said patents or application, except in new combinations or connected with new devices.

Having thus described my invention, what I claim as new, and desire to secure by Letters Patent, is—

1. A cooking-stove, which has only a direct draft from the fire-chamber to the exit-pipe, and with or without the oblique plate T attached to the top plate near the pipe-collar, the heating-chamber L, around the fire-box, in combination with the flue N in rear of the fire-box, the flue G under the oven, the flue F at the rear of the oven, valves O and O', substantially as and for the purposes herein described and set forth.

2. A cooking-stove, which has a heating-chamber, L, around the fire-box, and flues N, G, and F, valves O and O', in combination with a water-reservoir or reservoir and warming-closet attached to the rear end of such stove, substantially as and for the purposes herein described and set forth.

3. The water-tanks U attached to the sides of the heating-chamber L, and connected with a hollow perforated ring or chamber, c, by tubes a, which chamber c is located on top of

the chamber L, and forms the top part of the fire-box, substantially as and for the purposes herein described and set forth.

4. The heating-chamber L, flues N, G, and F, the valves O and O', in combination with the oven E, having the bottom valve s and rear-end valve r, substantially as and for the purposes herein described and set forth.

5. A cooking-stove, which has the heating-chamber L, flues N, G, and F, the valves O and O', in combination with a water-reservoir or reservoir and warming-closet attached to the rear part of such stove, and which has the flues n n' n'', the space or spaces f at the sides of reservoir, and with or without the valve k, substantially as and for the purposes herein described and set forth.

6. In a cooking-stove, which has a heating-chamber, L, around the fire-box, and hot-air flues N, G, and F, valve O or O', or both, the vertical plates R R placed in the flue G, substantially as and for the purposes herein-before described and set forth.
